UNITED STATES PATENT OFFICE

164,661

SUGAR BOWL

Eva S. Zeisel, New York, N. Y., assignor to United China and Glass Co., New Orleans, La., a corporation of Louisiana

Application October 3, 1950, Serial No. 12,429

Term of patent 14 years

(Cl. D44—15)

To all whom it may concern:

Be it known that I, Eva S. Zeisel, a citizen of the United States, residing at 431 Riverside Drive, New York, State of New York, have invented a new, original, and ornamental Design for Sugar Bowl, of which the following is a specification, reference being had to the accompanying drawing, forming a part hereof.

Fig. 1 is a side elevational view, with parts broken away, showing my new design of a sugar bowl;

Fig. 2 is an end elevational view, with parts broken away;

Fig. 3 is a top plan view;

Fig. 4 is a fragmentary horizontal sectional view, on line 4—4 of Fig. 1;

Fig. 5 is a fragmentary upright sectional view, through the bowl portion, on line 5—5 of Fig. 3.

I claim:

The ornamental design for a sugar bowl, as shown.

EVA S. ZEISEL.
